UNITED STATES PATENT OFFICE.

FRANK P. HAMILTON, OF CLEVELAND, OHIO.

BLOW-OFF VALVE.

972,370.

Specification of Letters Patent. Patented Oct. 11, 1910.

Application filed December 12, 1905. Serial No. 291,433.

To all whom it may concern:

Be it known that I, FRANK P. HAMILTON, a citizen of the United States, residing at Cleveland, in the county of Cuyahoga and State of Ohio, have invented certain new and useful Improvements in Blow-Off Valves, and do declare that the following is a full, clear, and exact description of the invention, which will enable others skilled in the art to which it appertains to make and use the same.

My invention relates to improvements in blow-off valves, and the improvement consists in a blow off valve provided with means adapted to regrind the valve seat members within the valve itself, all substantially as hereinafter shown and described and more particularly pointed out in the claim.

20 When foreign matter, such as scale or sedimentary deposits, lodges upon the valve seat complete closing of the valve is prevented and wire drawing or cutting of the seat is the result.

25 The object of my improvement is to provide means to apply more or less rotary pressure to the valve disk independent of its usual seating screw and whereby such deposits are ground to powder or broken up 30 so finely that perfect seating of the valve is obtained. The valve itself may also thus be ground to make its own seat and this may be done from time to time as occasion requires without removing the valve from its 35 connections and during the time it is under full boiler pressure.

Secondary to the above, but important nevertheless, is the detail construction of the valve and all its operating parts whereby 40 certain advantages in the use and life of the valve is obtained and especially in the convenience and saving of time in making repairs, all as hereinafter set forth.

In the accompanying drawings, Figure 1 45 is a side elevation of the valve, and Fig. 2 is a central sectional view at right angles to Fig. 1. Fig. 3 is a perspective view of the valve stem, and Fig. 4 is a perspective view of the valve disk.

50 Body A of the valve is in the form of a right angled elbow with a central through passage or opening 2 from top to bottom which is intersected by inlet passage or side opening 3. The ends of the elbow portions 55 have flanges wherewith a bolted connection

is made to like fittings on the steam line (not shown), but screw threaded connections may be employed instead. Passage 2 is contracted at its outlet end 5 and enlarged at its opposite end 6 over and above its central portion 7 wherein the tubular seat member 8 is removably held by friction when driven in place from above. Opening 7 has slightly flaring walls widest at its top and seat member 8 is tapering in the same degree to give a wedging fit, and when said member is worn beyond repair it may be removed by a suitable bar or ram inserted from below and which is adapted to engage inwardly extending lugs 9 on the bottom end of member 8, and which lugs are necessary for this purpose in view of the contracted outlet opening 5.

Valve disk B has a tapering or cone shaped end 10 adapted to seat within the flaring seat or mouth 12 of the thimble member 8, and is removably supported upon head 13 of operating valve stem 14. Valve B is disk shaped and has a grooved or rabbeted recess and side slot 15 at its top adapted to receive the partly circular and partly rectangular head 13 and whereby rotation to disk B is imparted. This detachable connection of disk B with stem 14 allows the replacement of old and worn out valve disks by new ones.

Valve stem 14 is supported to revolve within a sleeve 16 threaded in standard 17 of the packing head 18 which is bolted to the top of body A. A pair of arms 19 form part of hanger 17 and head 18, and a suitable recess or stuffing box 20 in head 18 about stem 14 is filled with packing 21 which is compressed and held in place by the male member 22 of the stuffing box on cross head 23. Two of the bolts used to secure head 18 upon body A have threaded extensions 24 passing through openings in cross head 23, and nuts 25 secure said cross head adjustably in place.

100 Stem 14 has a reduced upper end 26 which provides an annular shoulder or seat 27 for a steel collar 28 having a race upon its upper face opposed to a race within the opposite end of sleeve 16 and between which suitable balls 29 are seated to take up the end thrust when sleeve 16 is rotated by its operating wheel 30 to carry valve disk 8 to its seat. A second collar 31 with ball bearings 32 between it and the upper end of sleeve 16 110

is pinned to the outer end of valve stem 14, and serves to hold all the bearing parts in working relation as well as to provide for the end thrust to carry the valve away from 5 its seat.

- In operation, the valve is opened and closed by rotating wheel 30 and its attached sleeve 16, and in this operation valve disk B and stem 14 may or may not rotate. If deposits prevent perfect closure of the valve a 10 rotary action to disk B is positively obtained by rotating stem 14 by means of a wrench or other suitable engaging device adapted to fit over the angular end 34 of said stem. As 15 grinding continues, and whenever occasion requires, a gradually increasing pressure may be brought to bear upon the valve seat or the deposit thereon by rotating wheel 30 in the right direction.
- 20 The device is not limited solely to a blow off valve but has been so described because of its peculiar adaptability to that class of valves. Therefore, the claim is to be con-

strued to read on other forms of valves than as shown and described.

25

What I claim is:—

The main body and the valve adapted to be seated therein having a cylindrical stem of different diameters and collars seated upon the smaller portion of said stem and an 30 operating sleeve for said stem between said collars, in combination with a packing head having a stuffing box for said stem projecting into said body, and a threaded standard for said sleeve integral with but apart from 35 said head upon its outside, a cross head having a follower for said stuffing box and bolts to secure said packing head to the body and nuts to adjustably secure said cross heads upon said bolts.

40

In testimony whereof I sign this specification in the presence of two witnesses.

FRANK P. HAMILTON.
